UNITED STATES PATENT OFFICE

ANDREW HANAUER, OF COVINGTON, KENTUCKY.

IMPROVEMENT IN SCROLL-SAWING MACHINES.

Specification forming part of Letters Patent No. 44,304, dated September 20, 1864.

To all whom it may concern:

Be it known that I, ANDREW HANAUER, of Covington, in the county of Kenton and State of Kentucky, have invented a new and Improved Scroll-Sawing Machine; and I do hereby declare that the following is a full, clear, and exact description thereof, which will enable others skilled in the art to make and use the same, reference being had to the accompanying drawings, making a part of this specification, in which—

Figure 1 is a front sectional view of my invention, taken in the line $x x$, Fig. 2; Fig. 2, a transverse vertical section of the same, taken in the line $y y$, Fig. 1; Fig. 3, a vertical section of a portion of the same, taken in the line $z z$, Fig. 1; Fig. 4, a horizontal section of a portion of the same, taken in the line $x' x'$, Fig. 1; Fig. 5, a horizontal section of a portion of the same, taken in the line $y' y'$, Fig. 1; Fig. 6, a longitudinal central section of the pitman pertaining to the same; Fig. 7, an enlarged view of one end of a lever and a connecting-rod pertaining to the invention.

Similar letters of reference indicate like parts.

This invention consists in the employment or use of levers connected by rods and saws, the levers working on central fulcrum-pins, and one of the levers having its fulcrum-pin fitted in adjustable boxes, so that said lever, by means of certain mechanism hereinafter described, may be adjusted to strain the saws.

The invention also consists in a peculiarity of construction of the pitman which communicates motion to the saws, by which construction the journals on which the pitman is fitted may always be kept in a properly lubricated state.

A represents a framing to which a portion of the machinery is attached, and B is a table on which the plank or stuff to be sawed is placed.

C is a lever which is fitted centrally on a rock shaft, D, placed transversely in the lower part of the framing or support E of the table B, and F is a driving-shaft, which is also placed in the lower part of E, parallel with the rock-shaft D, and having a crank-pulley, G, on its inner end, and a driving-pulley, H, on its outer end.

In the framing A, directly over the table B, there is placed a lever, I, which is precisely similar to the lever C, and is in the same vertical plane with it. The fulcrum-shaft a of the lever I has its bearings in boxes b b, which are fitted in vertical slots c c and allowed to slide freely therein. The boxes b b rest on cams J J, placed one at the front and the other at the rear side of the post d, in which the boxes b b are fitted, said cams being fitted on a shaft, e, and the front cam having a lever, K, connected to it, which extends down and works over a rack, L, on the lower part of d, which holds the cams J in position. By adjusting this lever K the lever I may be raised for the purpose of straining the saws. The upper lever, I, has rods M M attached to its ends by pivots f, the latter passing through horizontal oblong slots g in the upper ends of the rods M, as shown clearly in Fig. 7. The lower ends of the rods M M are connected to vertical slides N N, which are fitted in guides O O, attached to the framing A, said guides, as well as the slides, being provided with oblique sides, as shown in Fig. 4.

P P are the saws, the upper ends of which are connected to the slides N N, the lower ends being connected to similar slides, Q Q, which are fitted in guides R R, attached to the under side of the table B, as shown clearly in Fig. 1. The slides Q Q are connected by rods S S to the ends of the lower lever, C. Thus it will be seen that two saws are employed in one and the same machine, and that both saws are made to face the front side of the machine, and the operators therefore work side by side, one to each saw, without interfering with each other. Each saw P works in a guide, T, which is at the lower end of a slide. These slides are fitted in the guides O O, directly back of the slides N N, and the slides U may be retained at any desired point by set-screws a^x.

V represents a pitman which is connected with the crank-pulley G and with the slide Q, which is directly above the crank-pulley. This pitman V is tubular, and it is filled with hemp or any suitable fibrous or absorbent material b^x, which will contain oil and serve to keep the journals C^x, on which the ends of the pitman work, properly lubricated at all

times. (See Fig. 6.) This is an important feature, for the pitman necessarily operates so rapidly in a scroll-sawing machine that its journals require to be kept perfectly lubricated in order to prevent wear.

On the shaft *a* of the upper lever, *I*, there is placed loosely a ratchet, *W*, with which a pawl, *d*^x, engages, and to the shaft *a* the inner end of a coil-spring, *X*, is attached, the outer end of said spring being connected to the ratchet *W*. This spring is designed to be wound up and used when only one saw is employed. In this case it serves to equalize the movement of the levers *C I* and insure a smooth action of the same, avoiding jars and concussions.

The saws *P P* are kept in a proper state of tension by adjusting the upper lever, *I*, through the medium of the cams *J J*, as previously referred to.

I would remark that the slides *N Q* may be made of two longitudinal parts, connected by set-screws, so that they may be expanded, when necessary, in order to compensate for

wear and thereby prevent unnecessary play of the same and consequent wear and tear.

The oblong slots *g* in the upper ends of the rods *M* admit of a lateral sliding of the latter to compensate for the combined movement of the lever *I*.

Having thus described my invention, I claim as new and desire to secure by Letters Patent—

1. The two levers *C I*, in combination with the two saws *P P*, and connecting-rods *M S* and slides *M Q*, arranged to operate in the manner, substantially as and for the purpose herein set forth.

2. The adjusting of the upper lever, *I*, through the medium of the cams *J J*, for the purpose of straining the saws, as herein specified.

3. The tubular pitman *v*, provided with fibrous or absorbent filling *b*^x, for the purpose herein set forth.

ANDREW HANAUER.
